CLAIM

The ornamental design for a paper punch, as shown and described.

DESCRIPTION

FIG. 1 is a front perspective view of a paper punch showing the new design;

FIG. 2 is a front elevational view thereof;

FIG. 3 is a rear elevational view thereof;

FIG. 4 is right side elevational view thereof;

FIG. 5 is a left side elevational view thereof;

FIG. 6 is a top view thereof;

FIG. 7 is a bottom view thereof; and,

FIG. 8 is a front perspective view thereof in an exploded condition.

The shading shown on the feet is intended to represent texture.

The broken lines indicate shading.
